CLAIM

The ornamental design for a hip carrier, as shown.

DESCRIPTION

This application contains related subject matter by a common inventor with the following applications:

U.S. patent application Ser. No. 14/247,406 titled “Baby Carrier with Removable Seat,” filed Apr. 8, 2014 by Khai Gan Chuah and issued as U.S. Pat. No. 9,314,112;
U.S. patent application Ser. No. 29/501,398 titled “Booster Seat Baby Carrier,” filed Sep. 3, 2014 by Khai Gan Chuah and issued as U.S. Pat. No. D755,508;
U.S. patent application Ser. No. 29/693,889 titled “Baby Carrier,” filed Jun. 5, 2019 by Khai Gan Chuah;
U.S. patent application Ser. No. 62/871,060, filed Jul. 5, 2019 by Khai Gan Chuah;
U.S. patent application Ser. No. 29/712,816 titled “Hip Seat Carrier,” filed Nov. 12, 2019 by Khai Gan Chuah; and,
U.S. patent application Ser. No. 16/854,812 titled “Baby Seat Carrier,” filed Apr. 21, 2020 by Khai Gan Chuah.
FIG. 1 is a front view of a hip carrier showing my new design;
FIG. 2 is a rear view thereof;
FIG. 3 is a right perspective view thereof;
FIG. 4 is a left perspective view thereof;
FIG. 5 is a right view thereof;
FIG. 6 is a left view thereof;
FIG. 7 is a top view thereof;
FIG. 8 is a top view of a hip carrier according to the present invention, wherein the belt has been detached for convenience of illustration;
FIG. 9 is a bottom view thereof;
FIG. 10 is a bottom view of a hip carrier according to the present invention, wherein the belt has been detached for convenience of illustration;
FIG. 11 is a front view of an alternate embodiment of hip carrier;
FIG. 12 is a rear view of the embodiment of FIG. 11;
FIG. 13 is a right perspective of the embodiment of FIG. 11;
FIG. 14 is a left perspective view of the embodiment of FIG. 11;
FIG. 15 is a right view of the embodiment of FIG. 11;
FIG. 16 is a left view of the embodiment of FIG. 11;
FIG. 17 is a top view of the embodiment of FIG. 11;
FIG. 18 is a top view of the embodiment of FIG. 11, wherein the belt has been detached for convenience of illustration;
FIG. 19 is a bottom view of the embodiment of FIG. 11;
FIG. 20 is a bottom view of the embodiment of FIG. 11, wherein the belt has been detached for convenience of illustration;
FIG. 21 is a front view of an alternate embodiment of hip carrier;
FIG. 22 is a rear view of the embodiment of FIG. 21;
FIG. 23 is a right perspective of the embodiment of FIG. 21;
FIG. 24 is a left perspective view of the embodiment of FIG. 21;
FIG. 25 is a right view of the embodiment of FIG. 21;
FIG. 26 is a left view of the embodiment of FIG. 21;
FIG. 27 is a top view of the embodiment of FIG. 21;
FIG. 28 is a top view of the embodiment of FIG. 21, wherein the belt has been detached for convenience of illustration;
FIG. 29 is a bottom view of the embodiment of FIG. 21; and,
FIG. 30 is a bottom view of the embodiment of FIG. 21, wherein the belt has been detached for convenience of illustration.
